UNITED STATES PATENT OFFICE.

ROBERT LEDING, OF WASHINGTON, DISTRICT OF COLUMBIA.

DESIGN FOR A HANDLE FOR SPOONS, FORKS, &c.

SPECIFICATION forming part of Design No. 20,339, dated November 18, 1890.

Application filed August 18, 1890. Serial No. 362,340. Term of patent 7 years.

To all whom it may concern:

Be it known that I, ROBERT LEDING, a citizen of the United States, residing at Washington, in the District of Columbia, have invented a new and original Design for Spoons; and I do hereby declare the following to be a full, clear, and exact description of the same.

The accompanying drawing represents a plan view of the upper surface of my newly-10 designed spoon.

The leading feature of my design consists in a representation of the Washington Monument, forming the main ornamentation of the spoon-handle, and surrounded by a wreath or garland entwined along the monument, and a 15 representation of the United States Capitol building, occupying the center of the bowl.

Referring to the drawing, A indicates the main body of the spoon-handle, having thereon 20 the representation of the Washington Monument and surrounded by the wreath or garland B.

C is the spoon-bowl having in its center the representation of the Capitol building located between the ends or terminals of the garland. 25

The design for the entire spoon presents to the eye the general effect of the Washington Monument entwined by a decorative wreath or garland and surmounted by the Capitol building.

The design for the spoon-bowl represents the Capitol building itself as located between wreathed leaves extending along a portion of the edges of the bowl.

I claim—

The design for a spoon herein shown and described.

In testimony whereof I affix my signature in presence of two witnesses.

ROBERT LEDING.
